UNITED STATES PATENT OFFICE.

FRED M. MOODY, OF WHITMAN, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed February 1, 1919. Serial No. 274,455.

To all whom it may concern:

Be it known that I, FRED M. MOODY, a citizen of the United States, residing at Whitman, in the county of Plymouth and 5 State of Massachusetts, have invented certain Improvements in Fastening-Inserting Machines, of which the following description, in connection with the accompanying drawings, is a specification, like reference 10 characters on the drawings indicating like parts in the several figures.

This invention relates to fastening inserting machines and has for its object the provision of improved means for moving the 15 work positioning means of such machines to and from its positions of adjustment.

The invention will be hereinafter shown and described, by way of example, as applied to a machine for inserting slugs in the 20 heels of shoes of the type disclosed in the patent to Casgrain, 786,190, dated March 28, 1905. The slugs are inserted for purposes of ornamentation or to enhance the 25 wearing qualities of the heel or both and are sometimes inserted in a plurality of rows parallel to the contour edge of the heel and to each other. Work positioning means in the form of a gage for determining the spacing of the rows of slugs from each other 30 and from the edge of the work constitutes the subject-matter of the patent to Casgrain 1,040,273, dated October 8, 1912.

Although the gage of the Casgrain patent has proved generally satisfactory, its use 35 has been attended by certain disadvantages such, for example, as the soiling of colored shoes by oil and grease from the machine with which the hands of the operator unavoidably become daubed in operating the 40 gage by the hand lever provided for such purpose. It is, moreover, desirable that means be provided by which the gage may be more quickly and easily moved to its various positions of adjustment than has 45 heretofore been possible.

A more particular object of the invention is to enable the insertion of the fastenings into the work without discoloration or other injury thereto and to facilitate the movement of the positioning means for the work 50 from one position of adjustment to another without the sacrifice of any of the advantages of such means as formerly constructed, such for example, as the determination of

fixed limits of adjustment between which it 55 may be moved without requiring the exercise of attention on the part of the operator to locate it in its correct position or to retain it therein. To this end, an important feature of the invention resides in a novel 60 combination of work positioning means movable from either of two positions of adjustment to the other and operable in either of such positions to determine the spacing of a row of fastenings from the edge of the 65 work, and mechanism constructed and arranged for operation by the leg of the operator to move said means from either of such positions of adjustment to the other and to retain it independent of the exertion 70 of force by the operator in either of such positions. The actuation of the work positioning means by such mechanism makes unnecessary the application of the hand of the operator to the machine while operating on 75 a shoe and thus enables him to avoid soiling the shoe. Moreover, inasmuch as the accurate presentation of the work to the machine requires the use of both of the operator's hands, it ensues that both the control of the work and the movement of the 80 gage are greatly facilitated by the operation of the gage by the leg of the operator, thus relieving him of the necessity of removing his hands from the work in changing the insertion of the fastenings from one row to 85 another.

An important feature of the invention further resides in operating means for the work positioning means comprising a pivoted rocking member having a projection extending beyond the fulcrum point of the member and converging to its end and means controlled by the projection for moving the rocking member alternately in opposite directions. Preferably, and as shown, 90 the rocking member diverges from one side of its fulcrum point and is produced past the fulcrum point to the other side to form a projection converging from the fulcrum point to its end. The actuator for the rocking member engages alternately with opposite sides of said member to move it in opposite directions, said actuator being operable in a path intermediate between the 95 limits of movement of the end of the projection occasioned by movement of the rocking member so that the projection directs 100 105

the actuator alternately against opposite sides of the rocking member.

Although the invention will be herein-after described in its application to the insertion of two rows of slugs into heels, it is recognized that its application is not restricted thereto but that it may be employed for instance, to determine the spacing of two rows of fastenings from each other and from the edge of the work irrespective of the character of the work or to determine adjustably the insertion of a single row of fastenings from the edge of the work. Moreover, the invention in certain of its aspects constituted by various combinations of elements may be used advantageously in still other relations. It is, therefore, intended that the scope of the invention shall be limited only as required by the claims.

20 The invention also resides in various arrangements and combinations of parts which will appear as the description proceeds and will be pointed out in the appended claims.

25 In the drawings,

Fig. 1 is a view in elevation of a slugging machine embodying the invention.

Fig. 2 is a view in side elevation of the gage and the connections thereto from the 30 gage operating means;

Fig. 3 is a view in plan of the means for operating the gage;

Fig. 4 is a view in cross-section taken along the line 4—4 of Fig. 3 and looking in 35 the direction of the arrow;

Fig. 5 is a view in cross-section of the means for directing the actuator in its movements taken along the line 5—5 of Fig. 3, looking in the direction of the arrow; and

40 Fig. 6 illustrates the rocking member and the actuator bar in the positions that such parts assume upon the operation of the bar to move the rocking member in the direction indicated by the large arrow.

45 The machine in which the invention is illustrated as embodied comprises a column 2 which supports a head 4 upon which the fastening inserting instrumentalities of the machine (not shown) are mounted. Work 50 positioning means is carried by said head 4 in the form of a gage 6 designed for engagement with the edge of the work to determine the spacing of the row or rows of fastenings from the edge of the work and from 55 each other. The gage support 7 is fulcrumed to the machine frame at 8 so that the gage may be moved downwards to inoperative position to permit more facile access to the fastening inserting instrumentalities.

60 The gage is maintained in operative position by a spring-pressed plunger 10 slidably mounted in a seat formed in the head 4 of the machine and is formed with an upturned portion 12 provided with a slot 14 65 which receives a pin 16 mounted eccentrically

ly on a shaft 18 disposed transversely of the head 4. With this construction, oscillation of the shaft 18 will effect movement of the gage 6 from one of its positions of adjustment to the other so that the insertion of two rows of fastenings parallel to each other may be determined. The elements thus far described may be and, as shown, are identical in construction and arrangement with the corresponding elements of the Casgrain patents above cited and form in themselves no part of the present invention.

In the illustrated construction, the shifting of the gage 6 to and from its positions of adjustment is effected by devices carried by a bracket 20 mounted on the horizontal portion of the column 2 of the machine intermediate between the upright portion 22 of the column and the sleeved member 24 which extends upwardly from the forward part of the horizontal portion of the column and is adapted to receive the horn post of the machine. The bracket 20 is detachably connected to the column 2 by suitable means, such as screws or the like, and the gage shifting devices carried thereby comprise a rocking member 26 fulcrumed at 28 to the bracket 20, knee lever actuated means for moving the rocking member, and means operated by the rocking member for moving the gage, said last-mentioned means comprising an arm 30 pivoted to the bracket 20 at one side of the rocking member 26 and extending over the body of the rocking member to one side of its fulcrum point 28. The 95 arm 30 is slotted at 32 to receive a block 34 carried by the rocking member 26 and movable in the slot of the arm. The free end of the arm has swivelled therein (see Fig. 4) a forked member 35 to which is fulcrumed one end of a link 36 joined at its other end to the short upright arm 38 of the bell crank 40. The bell crank 40 is pivoted near one end of the bracket 20 and is connected by a second link 42, which, as shown, includes a 100 turn-buckle, for purposes of adjustment, to the arm 44 removably secured to the shaft 18 by a set screw 45 threaded into the end of the shaft. If, for any reason, it is desirable in a special case to move the gage by 105 a hand lever as described in Patent No. 1,040,273, the mechanism of the present invention may be detached readily from the shaft 18 and from the column 2 of the machine and the operating means shown in 110 said patent substituted therefor. Operating means in accordance with the present invention may also be readily applied to a machine in substitution for that of the patent.

The arrangement of the block 34 relative to 115 the rocking member 26 and arm 30 is such that when the rocking member is oscillated about its fulcrum 28 the block and consequently the free end of the arm is moved toward and away from the fulcrum point 28 of 120 130

the rocking member in a direction to effect movement of the link 36 and consequently of the gage 6. The block 34 when moved toward the inner end of the slot 32 of the arm 30 as 5 sumes a position between the fulcrum point 28 of the rocking member 26 and the pivot of the arm 30. Movement of the rocking member 26 in a direction to carry the block in such direction is adjustably limited by a 10 screw or the like 46 and a spring 48 connected to the free end of the arm 30 and to the fixed brace 50 acts through the arm 30 and block 34 to urge the rocking member against the stop 46 which thereby determines 15 the forward position of adjustment of the gage 6. Movement of the rocking member 26 in a direction to carry the block 34 toward the free end of the arm 30 is limited by the engagement of the block with a stop 20 52 (see Fig. 4) to a position such that the spring 48 operates against the block substantially in alignment with the pivot 28 of the rocking member so that it is held in position by the spring. Inasmuch as the stop 25 52 determines the rearward position of adjustment of the gage it follows that the gage is retained in either of its positions of adjustment automatically without the exertion of force on the part of the operator. The 30 lines A and B (see Fig. 6) indicate the limits of movement of the free end of the arm 30 upon movement of the rocking member in the direction indicated by the arrow and in the opposite direction respectively.

35 The rocking member is formed at the side of its fulcrum point substantially opposite from the block 34 with a projection 54 which converges from the fulcrum point of the rocking member to its end 56. An actuator 40 bar 58 normally spaced from the end 56 of the projection 54 is operable to move the rocking member about its fulcrum, said member being constructed with surfaces diverging from the fulcrum point so that upon engagement 45 of the actuator therewith, the rocking member will be moved in one direction or the other determined by the side of said member against which the actuator operates. Preferably, and as shown, the rocking member 50 is provided at opposite sides of its fulcrum point 28 with concave surfaces 60 which insure engagement of the bar with the rocking member in a manner to effect movement of said member. The arrangement 55 of the rocking member 26 and the actuator 58 is such that movement of the rocking member from one of its limits of movement to the other occasions movement of the end of the projection 54 to one side or the 60 other of the path of movement of the actuator, or, in other words, the actuator 58 moves in a path intermediate between the limits of movement of the end 56 of the projection 54 occasioned by movement of the rocking 65 member. Consequently, upon operation of

the actuator, the rocking member is moved alternately in opposite directions.

The actuator bar 58 is normally alined with the fulcrum 28 of the rocking member, and the initial part of its movement is directed in a path substantially in line with the fulcrum to engage with a side of the projection 54. The directing means for the actuator is so constructed as to permit movement of the actuator bar laterally of the fulcrum point 28 of the rocking member so as to allow the end of the bar to move along either of the diverging surfaces of the rocking member (see Fig. 6). Preferably, and as illustrated, said directing means comprises slides 62 and 64 disposed on opposite sides of the bar 58 and mounted on the bracket 20 within the brace 50. The slides 62 and 64 are normally urged toward each other and against the sides of the bar by springs 66 and a stop 68 limits the movements of said slides under the impulse of the springs and determines the normal position of the bar. When the actuator bar is thrust against the side of the rocking member as indicated in Fig. 6, its end is wedged laterally by the surface of said member thereby moving the slide 62 against the resistance of its spring 66, the slide 64 being prevented from following the bar in its lateral movement by the stop 68. Consequently, when the bar 58 is withdrawn from engagement with the rocking member, it will be moved back to its normal position in alinement with the fulcrum 28. When the actuator bar 58 engages the other side of the rocking member, the operation is the same as above outlined except that the slide 64 is moved against the tension of its spring and the slide 62 is limited in its movement by the stop 68 so as to insure the return of the actuator bar to normal position by the slide 64 under the impulse of its spring 66. 90

The actuator bar 58 is operated by a knee lever to which the bar is pivoted at 71 so that it may partake of the lateral movements hereinbefore described. The knee lever is in turn pivoted at 72 to a forward extension 73 of the bracket 20, and a spring 74 is interposed between a part on the lever 70 and the end of a seat in the bracket 20 so as to urge the lever 70 against the stop 76 and thus maintain the actuator 58 in inoperative position spaced from the projection 54 of the rocking member. The alternate 100 movements of the rocking member and consequently of the edge gage in opposite directions are, as will be apparent from the foregoing, effected by movements of the knee lever and the actuator bar in the same direction.

Having described my invention, what I claim as new, and desire to secure by Letters Patent of the United States is:

1. In a fastening inserting machine, fas- 130

tening inserting instrumentalities, work positioning means movable from either of two positions of adjustment to the other to determine the insertion of rows of fastenings in 5 a piece of work parallel to each other and to the edge of the work, and means constructed and arranged to move the work positioning means from either of such positions of adjustment to the other, said means comprising a pivoted rocking member and actuating means for the rocking member normally disconnected therefrom and including a knee lever.

2. In a fastening inserting machine comprising a column and a head mounted thereon, an edge gage movable on said head from either of two positions of adjustment to the other to determine the insertion of rows of fastenings parallel to each other and to the 10 edge of the work, a shaft disposed transversely of the head and operatively connected to the edge gage, and knee lever actuated means mounted on the column of the machine for operating said shaft to move the 15 edge gage from one position of adjustment to the other, and comprising a pivoted rocking member and a reciprocating actuator therefor.

3. In a fastening inserting machine having a column with a substantially horizontal portion and a substantially vertical portion rising therefrom, a head mounted thereon and a sleeved member extending from the horizontal portion of the column and spaced 35 forwardly of said vertical portion, said sleeved member being adapted to receive the horn post of the machine, the combination of an edge gage movable on the head from either of two positions of adjustment to the 40 other to determine the insertion of rows of fastenings parallel to each other, a bracket mounted on the horizontal portion of the column of the machine intermediate between the vertical portion of the column and the 45 sleeved member, devices carried by the bracket for operating the edge gage, connections between said devices and the edge gage, and a knee lever fulcrumed on said bracket for actuating said devices.

4. In a fastening inserting machine, fastening inserting instrumentalities, work positioning means movable from either of two positions of adjustment to the other to determine the insertion of rows of fastenings in 50 a piece of work parallel to each other and to the edge of the work, and means for moving said work positioning means to and from said positions of adjustment comprising a pivoted rocking member having a projection extending beyond the fulcrum point of said member and converging to its end, an actuator for moving 55 said rocking member about its fulcrum, means for moving the actuator in a path intermediate between the limits of move-

ment of the end of said projection occasioned by movement of the rocking member so that the actuator is caused to engage said member alternately on opposite sides of said projection to effect movement of the member alternately in opposite directions, and connections between the rocking member and the work positioning means.

5. In a fastening inserting machine, the combination of a pivoted rocking member 70 having a projection extending beyond the fulcrum point of said member and converging to its end, and means controlled by the projection for moving the rocking member alternately in opposite directions.

6. In a fastening inserting machine, the combination of a pivoted rocking member having a projection extending beyond the fulcrum point of said member and converging to its end, an actuator controlled by the 80 projection for moving the rocking member and operable upon movement in the same direction to move the rocking member in opposite directions, and means for maintaining said actuator normally in inoperative relation to the rocking member.

7. In a fastening inserting machine, the combination of a pivoted rocking member having a projection extending beyond the fulcrum point of said member and converging to its end, an actuator for moving the rocking member about its fulcrum, and means for moving the actuator in a path intermediate between the limits of movement of the end of said projection occasioned by movement of the rocking member so that the actuator is caused to engage alternately on opposite sides of said projection to effect movement of the rocking member alternately in opposite directions.

8. In a fastening inserting machine, the combination of a stationary support, a rocking member fulcrumed on the support and having a projection extending beyond the fulcrum point of said member, said projection being formed to diverge from a point spaced from the fulcrum point of said member to the fulcrum point, and an actuator for the rocking member constructed and arranged to engage the 100 projection of the fulcrum member alternately on opposite sides to move said member about its fulcrum alternately in opposite directions.

9. In a fastening inserting machine, the combination of a pivoted rocking member diverging from a point spaced from the fulcrum point of said member to and beyond the fulcrum point thus forming a projection on said member converging from the 110 fulcrum point to said first-mentioned point, and actuating means for the member comprising a bar directed normally in a path substantially in alignment with the fulcrum point of said member and intermediate be- 125 130

- between the limits of movement of the end of said projection occasioned by movement of said member, the character of the divergence of said member beyond its fulcrum point in the direction of operating movement of the bar being such as to cause it to be engaged by said bar in a manner such as to effect turning movement of the rocking member about its fulcrum so that upon successive actuations of said bar the rocking member is moved first in one direction and then in the other by engagement of the end of the bar with its opposite sides, the bar being directed alternately against such sides by the projection on said member. 15
10. In a fastening inserting machine, the combination of a pivoted rocking member formed on both sides of its fulcrum point with concave surfaces and having a projection extending beyond one side of the fulcrum point and converging to its end, actuating mechanism for the rocking member comprising a bar normally substantially aligned with the fulcrum point of the rocking member, and means for moving the bar into engagement with the concave surfaces of the rocking member to operate said member, said means acting to move the bar in a path between the limits of movement of the end of said projection occasioned by movement of the rocking member so that said projection directs the bar alternately against said concave surfaces to move the member alternately in opposite directions. 20
15. 11. In a fastening inserting machine, the combination of a pivoted rocking member formed on both sides of its fulcrum point with concave surfaces and having a projection extending beyond one side of the fulcrum point and converging to its end, an actuator for the rocking member, means tending normally to confine the actuator to a path of movement substantially in alignment with the fulcrum point and between the limits of movement of the end of the projection occasioned by movement of the rocking member but constructed to permit lateral movement of the actuator into engagement with the concave surfaces of said member, and means for moving the actuator into engagement with the concave surfaces of the rocking member to operate said member, said actuator being directed by said projection alternately against said concave surfaces to move the rocking member alternately in opposite directions. 25
12. In a fastening inserting machine, the combination of a pivoted rocking member having a projection extending beyond the side of the fulcrum point and converging to its end, an actuator for the rocking member movable in a path substantially in line with the fulcrum point of the rocking member, and means for determining the limits of movement of the rocking member such that, 30
- when the member is at the limit of its movement in one direction, the end of said projection is disposed at one side of the path of movement of the actuator and when the member is at the limit of its movement in the opposite direction, the end of said projection is disposed at the other side of said path so that upon successive operations of the actuator, the rocking member is moved alternately in opposite directions. 35
13. In a fastening inserting machine, an edge gage movable from either of two positions of adjustment to the other to determine the insertion of rows of fastenings in a piece of work parallel to each other and means for moving the gage from one position of adjustment to the other comprising a pivoted rocking member, an arm fulcrumed at one side of the rocking member, a block carried by the rocking member and movable in a slot in the arm, a spring normally tending to move the arm in one direction, means for limiting the movement of the rocking member in such direction to determine one of the positions of adjustment of the gage in which it is maintained by the spring, and means for actuating the rocking member to move the gage to the other position of adjustment constructed and arranged to position the block in the arm so as to lock the arm against movement by the spring thereby to retain the gage in such other position of adjustment. 40
14. In a fastening inserting machine, the combination of a pivoted rocking member having a projection extending beyond its fulcrum point and formed to diverge from the end of the projection to and beyond the fulcrum point, an actuator for the rocking member, means tending normally to confine the actuator to a path of movement substantially in alignment with the fulcrum point and between the limits of movement of the end of the projection occasioned by movement of the rocking member but constructed to permit lateral movement of the actuator into engagement with the diverging surfaces of said member beyond the fulcrum point of said member in the direction of movement of the actuator, and means for moving the actuator into engagement with said diverging surfaces to operate said member, said actuator being directed by said projection alternately against said surfaces to move such member alternately in opposite directions. 45
15. In a fastening inserting machine, the combination of a pivoted rocking member having a projection extending beyond its fulcrum point and formed to diverge from the end of the projection to and beyond the fulcrum point, an actuator movable substantially in line with the fulcrum point of the rocking member and adapted to engage either of the sides of said projection to move the rocking member in one direction or the 50

other determined by the side of the projection engaged by the actuator, a knee lever for moving said actuator, connections between the knee lever and said actuator permitting movement of the actuator laterally of the sides of said projection, and means tending to return the free end of the actuator to its normal position.

16. In a fastening inserting machine, an edge gage movable from either of two positions of adjustment to the other to determine the insertion of rows of fastenings in a piece of work parallel to each other and means for moving the gage to and from such positions of adjustment comprising an actuator normally operatively disconnected from the gage and operable upon movement in the same direction to effect movement of the gage in opposite directions.

17. In a fastening inserting machine, an edge gage movable from either of two positions of adjustment to the other, to determine the insertion of rows of fastenings in a piece of work parallel to each other, means for moving the gage to and from such positions of adjustment comprising an actuator normally operatively disconnected from the gage and operable upon movement in the same direction to move the gage to and from its positions of adjustment, and means independent of the actuator for retaining the gage in any position of adjustment to which it may be moved.

18. In a fastening inserting machine, an edge gage movable from either of two positions of adjustment to the other to determine the insertion of rows of fastenings in a piece of work parallel to each other, means for moving the edge gage from one position of adjustment to the other comprising a rocking member, an arm pivoted adjacent to the rocking member, connections between the rocking member and the arm operable to effect movement of the arm upon operation of the rocking member, positive connections between the arm and the gage for effecting movement of the gage upon movement of the arm, and an actuator operable upon movement in the same direction to effect movement of the rocking member and, consequently, of the gage in opposite directions.

19. In a fastening inserting machine, an edge gage movable from either of a plurality of positions of adjustment to the other to determine the insertion of rows of fastenings in a piece of work parallel to each other, an arm operatively connected to the edge gage, yielding means normally tending to move the arm in a direction to move the edge gage from one of said positions of adjustment to the other, a rocking member operatively connected to the arm, an actuator for shifting the rocking mem-

ber to move said arm to and from said positions of adjustment, and means for reciprocating the actuator.

20. In a fastening inserting machine, an edge gage movable from either of two positions of adjustment to the other to determine the insertion of rows of fastenings in a piece of work parallel to each other, an arm operatively connected with the gage and having a slot formed therein, yielding means operable on the arm and tending to move the gage forwardly, and means for moving the gage backwardly against the resistance imposed by said yielding means, comprising a pivoted member and a block carried by the pivoted member and slidably in the slot, said arm being formed to arrest the movement of the block in the slot after the main portion of the block has been moved past a line extending through the fulcrum point of the pivoted member and in the direction of movement of the arm, thus locking the gage in its rearward position.

21. In a fastening inserting machine, an edge gage movable between forward and rearward positions of adjustment to determine the insertion of rows of fastenings in a piece of work parallel to each other, yielding means for moving the gage toward its forward position of adjustment, means for moving the gage backwardly against the resistance imposed by said yielding means, and means for limiting the movement of the gage under the action of the yielding means to its forward position of adjustment, constructed to retain the gage at its rearward position of adjustment against the action of the yielding means.

22. In a fastening inserting machine, an edge gage movable from either of two positions of adjustment to the other to determine the insertion of rows of fastenings in a piece of work parallel to each other and means for moving the gage from one position of adjustment to the other comprising a pivoted rocking member an arm fulcrumed at one side of the rocking member, a block carried by the rocking member and movable in a slot in the arm, a spring normally tending to move the arm in one direction, means for limiting the movement of the rocking member in such direction to determine one of the positions of adjustment of the gage in which it is maintained by the spring, and means for actuating the rocking member to move the gage to the other position of adjustment constructed and arranged to position the block in the arm so as to lock the arm against movement by the spring thereby to retain the gage in such other position of adjustment.

In testimony whereof I have signed my name to this specification.

FRED M. MOODY.
